SLAG DEFLECTOR

Fred J. Chatel, Detroit, Mich.

Application July 14, 1932, Serial No. 622,561

9 Claims. (Cl. 122—6)

This invention relates to a slag deflecting device adapted to be associated with a furnace wall or the like.

One of the primary objects of this invention is to provide a device of the above mentioned character which, when installed in a furnace wall, will prevent the formation of large clinkers or slag sheets on this wall.

A further object of this invention is to provide a device of the above mentioned character which will prevent slag or wall clinkers from falling on to the fuel bed of the furnace adjacent the walls, with the result that improved efficiency of combustion will be obtained together with a reduction in the burning of stoker iron.

Still further the invention contemplates the provision of a device of the above mentioned character which in use will provide for the discharge of slag from the furnace walls in such small quantities on the fuel bed that the slag may be carried out with the burned fuel.

Numerous other objects and advantages of this invention will become more apparent as the following description proceeds, particularly when reference is had to the accompanying drawing, wherein:

Fig. 1 is a semi-diagrammatic sectional view through a furnace showing a wall of the furnace with a deflecting device constructed in accordance with the teachings of this invention associated with the same;

Fig. 2 is a sectional view taken substantially on the line 2—2 of Fig. 1;

Fig. 3 is a sectional view taken substantially on the line 3—3 of Fig. 1.

In the operation of furnaces, considerable difficulty is experienced with the slag which deposits on the furnace walls. This slag forms a large sheet on each wall, a sheet sometimes attaining the weight of one or two tons, in large furnaces. These sheets of slag, when they become too heavy to adhere to the wall, crack or break and fall on to the fuel bed of the furnace, resulting in a decrease in the efficiency of combustion and resulting also frequently in a burning of the stoker parts, thus necessitating replacement of parts of the stoker or fuel feeding mechanism.

The present invention contemplates the elimination of the above mentioned difficulties by providing deflecting ledges associated with the furnace walls. These ledges may be made of refractory, carborundum, metal or other heat resisting material and can be placed in any or all of the walls of the furnace. These ledges are so shaped that they project inwardly toward the

combustion chamber of the furnace and overhang the subjacent portions of the furnace wall. These ledges prevent the formation of large clinkers or slag sheets on the furnace walls below them and provide for the melting of the slag and relatively slow dripping of the same on to the fuel bed whereby the slag may be removed with the burned fuel.

Referring then particularly to the drawing wherein like reference characters designate corresponding parts throughout all views, the numeral 10 designates the combustion chamber of a furnace designated generally by the reference character 11. The numeral 12 designates one wall of this furnace, this wall being shown as comprising the blocks 13 through which the tubes 14 extend, in accordance with the usual construction of water cooled furnace walls.

The furnace is shown as being provided with a fuel feeding mechanism which may comprise a 20 Taylor multiple retort and rear dump stoker having alternately arranged retorts 15 and tuyère rows 16. As usual, the fuel is fed by rams (not shown) into the forward ends of the retorts 15 underneath the fuel bed and is moved longitudinally of the retorts toward the ash pit 18 by suitable pushers 17 which in effect form stepped bottom walls of said retorts. The action of the pushers is such that the fuel is fed into the fuel bed and laterally on to the tuyère rows 16. Thus 30 the fuel feeding mechanism provides a moving fuel bed at the bottom of the combustion chamber, in accordance with the usual practice.

In accordance with the teachings of this invention, the wall 12 is provided with slag deflecting devices designated generally by the reference character 20. Each device comprises a series of blocks 21 positioned in juxtaposition to each other in the manner clearly illustrated in Figs. 1 and 3 of the drawing. The blocks are shaped to provide 40 downwardly and inwardly inclined surfaces 22 and vertical faces 23 so that when the blocks are assembled, downwardly facing shoulders 24 are formed, the edges 25 of which overhang the subjacent portions of the furnace wall.

In the form of construction shown in Fig. 1 of the drawing, the blocks 21 are substituted for certain of the blocks 13, the tubes 14 extending through the blocks 21 in the manner clearly illustrated in Fig. 3 of the drawing. Further, the 50 blocks are so arranged as to form three ledges at different elevations on the furnace wall, the adjacent ends of the ledges slightly overlapping each other. The arrangement is such that the ledge or deflecting device which is at the highest 55

elevation is at the higher end of the stoker, while the device which is at the lowest elevation is at the lowest end of the stoker. Thus adjacent each portion of the stoker there is provided a deflecting ledge or device incorporated in the furnace wall at a relatively short distance above the normal level of the fuel bed formed by the stoker.

In operation it will be found that the deflecting ledges will arrest clinker or slag sheet formation 10 at the inclined surfaces 22 and on the furnace wall above these surfaces. This results from the inclined surface of the device acting as a ledge or support for the clinker or slag formation above it.

15 Each device will further function to prevent or diminish the clinker or slag sheet formation on the furnace wall surface immediately below the device. This is effected by the device acting as a cutoff preventing the slag formation above the device from accumulating and extending on to the wall surface below the device.

Further, it will be noted that the surface 23 of each device will be spaced further from the cooling tubes 14 than the remainder of the furnace 25 wall, with the result that the slag on the faces 22 and 23 of each device will be at a relatively high furnace temperature, with the result that the slag on these faces will melt and drip slowly on to the fuel bed within the furnace. This slow 30 discharge of the molten slag on to the fuel bed will not be sufficient to disrupt the fuel bed, the slag being discharged in such small quantities that it may be carried out with the moving fuel bed to the ash pit of the furnace. Thus the invention provides for the constant slow discharge 35 of the deposited slag on to the moving fuel bed of the furnace and thus the continuous removal of this slag from the furnace with the burned fuel.

From the above it will be apparent that the 40 invention provides a slag deflecting device which may be associated with any or all of the walls of a furnace. The device function to prevent the formation of large sheets of slag on the furnace walls and also prevent the falling of slag or wall 45 clinkers on to the fuel bed near the wall. This results in improved efficiency of combustion and a reduction in the burning of stoker parts, thus eliminating the necessity of frequently replacing the stoker parts.

50 The devices are so arranged and constructed that the slag will drop from the same in small quantities on to the fuel bed so that the slag will be carried out in small quantities with the burned fuel. The walls are shown as being imperforate 55 and may be either in the form of water walls or plain refractory walls, dependent entirely upon the type of furnace with which the construction is associated.

While the invention has been described with 60 some detail, it is to be understood that the description is for the purposes of illustration only and is not definitive of the limits of the inventive idea. The right is reserved to make such changes in the details of construction and arrangement of 65 parts as will fall within the purview of the attached claims.

What I claim as my invention is:

70 1. In combination, an upright combustion chamber wall having horizontal courses of refractory blocks, and means for preventing the formation of large clinkers or slag sheets on said wall while providing for the gradual discharge from said wall onto an inclined fuel bed beside said wall of clinkers and slag in small quantities only, including staggeredly arranged rows of re-

fractory blocks set in and projecting laterally from the horizontal courses of said wall, the arrangement being such that the row at the highest elevation is toward one end of said wall while the row at the lower elevation is toward the other end of said wall. 5

2. In combination, an upright combustion chamber wall having horizontal courses of refractory blocks, and means for preventing the formation of large clinkers or slag sheets on said wall while providing for the gradual discharge from said wall onto an inclined fuel bed beside said wall of clinkers and slag in small quantities only, including stepped rows of refractory blocks set in the horizontal courses of the wall and projecting laterally therefrom, the arrangement being such that the row at the highest elevation is toward the higher end of the fuel bed while the row at the lowest elevation is toward the lower end of said fuel bed. 15 20

3. In combination, an upright combustion chamber wall having horizontal courses of refractory blocks, and means for preventing the formation of large clinkers or slag sheets on said side, while providing for the gradual discharge from said side onto an inclined fuel bed beside said wall of clinkers and slag in small quantities, including rows of refractory blocks set in and projecting laterally from the horizontal courses of said wall, said rows being arranged in 25 stepped relation with the step at the highest elevation at the higher end of the fuel bed and the step at the lowest elevation at the lower end of said fuel bed. 30

4. In combination, an upright combustion chamber wall having horizontal courses of refractory blocks, and means for preventing the formation of large clinkers or slag sheets on said wall while providing for the gradual discharge from said wall onto an inclined fuel bed beside 40 said wall of clinkers and slag in small quantities, including a stepped ledge construction on an upright side of said wall, each step comprising a substantially straight row of refractory blocks set in and projecting laterally from said wall, the 45 arrangement being such that the step at the highest elevation is at the higher end of the fuel bed while the step at the lower elevation is at the lower end of said fuel bed. 50

5. In combination, an upright combustion chamber wall having horizontal courses of refractory blocks, and means for preventing the formation of large clinkers or slag sheets on said wall while providing for the gradual discharge from said wall onto an inclined fuel bed beside 55 said wall of clinkers and slag in small quantities, including substantially horizontal ledges set in and projecting laterally from an upright side of said wall, said ledges being in stepped relation with the ledge at the highest elevation at the 60 higher end of the fuel bed and the ledge at the lowest elevation toward the lower end of said fuel bed.

6. In combination, an upright combustion chamber wall having horizontal courses of refractory blocks, and means for preventing the formation of large clinkers or slag sheets on an upright side of said wall, while providing for the gradual discharge from said side onto a downwardly and rearwardly inclined fuel bed beside 70 said wall of clinkers and slag in small quantities including three ledges set in said horizontal courses and projecting laterally from the upright side aforesaid of said wall at different elevations, the adjacent ends of the ledges slightly over- 75

lapping each other, the arrangement being such that the ledge at the highest elevation is at the forward end of said wall, while the ledge at the lowest elevation is adjacent the rear end of said wall.

5. 7. In combination, an upright combustion chamber wall having horizontal courses of refractory blocks, and means for preventing the formation of large clinkers or slag sheets on an upright side of said wall, while providing for the gradual discharge from said side onto a downwardly and rearwardly inclined fuel bed beside said wall of clinkers and slag in small quantities including stepped ledges set in the horizontal courses of said wall, the arrangement being such that the uppermost step is at the forward end of said wall, while the lowermost step is adjacent the rear end of said wall, said ledges being rigid with and projecting laterally from said wall.
10. 8. In combination, an upright combustion chamber wall having horizontally extending courses of brick, and means including stepped ledges set in said courses of brick for preventing the formation of large clinkers or slag sheets on said wall, while providing for the gradual discharge from said wall onto an inclined fuel bed
15. 9. In combination, an upright combustion chamber wall having horizontal courses of refractory blocks, and means for preventing the formation of large clinkers or slag sheets on said wall while providing for the gradual discharge from said wall onto a downwardly and rearwardly inclined fuel bed beside said wall of clinkers and slag in small quantities, including blocks set in the horizontal courses aforesaid and being cor-

15. 5. 9. 10. 15. 20. 25. niced to provide a series of overlapping steps on the inner surface of said wall between the upper and lower edges thereof, said steps being in part non-overlapping, the arrangement being such that the step at the highest elevation is adjacent the highest end of the inclined fuel bed while the step at the lowest elevation is toward the lowest end of said fuel bed.
